Patented Oct. 23, 1917.

FIG. 1.

FIG. 2.

Inventor

Jacob J. Bram,

By his Attorneys

Edgar Hale F.B.

UNITED STATES PATENT OFFICE.

JACOB J. BRAM, OF PERTH AMBOY, NEW JERSEY.

SUPPORT FOR WASHTUBS, TANKS, SINKS, AND THE LIKE.

1,243,697.

Specification of Letters Patent. Patented Oct. 23, 1917.

Application filed April 18, 1917. Serial No. 162,857.

To all whom it may concern:

Be it known that I, JACOB J. BRAM, a citizen of the United States, and residing at Perth Amboy, in the county of Middlesex and State of New Jersey, have invented certain new and useful Improvements in Supports for Washtubs, Tanks, Sinks, and the like, of which the following is a specification, such as will enable those skilled in the art to which it appertains to make and use the same.

This invention relates to supports for washtubs, tanks, sinks, lavatory basins, closet basins, and the like made of porcelain or other earthenware, and particularly to legs for receptacles of the class specified and made of the same material, and the object of the invention is to provide improved legs and improved means for connecting the legs of receptacles of the class specified with said receptacles whereby they may be supported independent of or without connection with a wall or partition adjacent to which they are placed.

The invention is fully disclosed in the following specification, of which the accompanying drawing forms a part, in which the separate parts of my improvement are designated by suitable reference characters in each of the views, and in which:

Figure 1 is a perspective view showing my improvement applied to washtubs made of porcelain;

Fig. 2 a sectional view of one end portion of one of the washtubs shown in Fig. 1 and showing the details of my improvement;

Fig. 3 a section on the line 3—3 of Fig. 2; and,

Fig. 4 a view similar to Fig. 2 but showing a modification.

In the drawing forming part of this specification, I have shown at *a* in Fig. 1 two ordinary washtubs made of porcelain or other earthenware and placed adjacent to a wall *b* and on a floor *b*² in the usual manner, and in the practice of my invention, I provide the tubs *a* with legs *c* which are also made of porcelain or other earthenware, and the legs *c* are provided with metal rods *d* which are passed therethrough and project from the upper or larger ends of the legs *c* as shown at *d*², and the projecting portions *d*² of the rods *d* are threaded to engage nuts *e* which are countersunk in the

bottoms of the tubs *a* and secured therein by cement, as shown at *e*².

The nuts *e*, in the construction shown, are provided with side recesses *e*³, and the cement enters these recesses to securely lock or hold the said nuts in position, but my invention is not limited to any particular means of locking the nuts *e* in the bottoms of the tubs *a* and any suitable means may be employed for accomplishing this result. 60 The rods *d* may also be anchored or secured in the legs *c* in any desired manner, and said rods are preferably provided at their lower ends with heads *d*³ which are countersunk as shown in Fig. 2, and when the legs *c* are 70 made in this manner and connected with the tubs, as shown and described, they form a firm support for the tubs and the water discharge pipes *f* may be connected with the tubs in the usual manner.

In the construction in Fig. 4 the rods *b* which pass through and form a part of the legs *c* are provided at their lower ends with thimble-shaped anchor devices which are countersunk in said legs and secured on said rods and which are provided with flanges through which are passed screws *h* for securing the legs to the floor and by means of this construction the tubs may be supported and secured to the floor by the legs 85 with which they are provided.

In the practice of my invention the legs *c* are made up in stock and may be shipped independent of the tubs and the legs *c* may be applied to the tubs whenever desired, or 90 in the operation of placing said tubs in position, and the rods *d* serve to protect the legs and prevent them from being broken in shipment or otherwise.

Although I have shown and described my improvement as a means of supporting washtubs, tanks or the like, when made of porcelain or similar material without connecting said tubs, tanks or the like with a wall or partition adjacent to which they are placed, it will be understood that said tubs, tanks or the like may be connected with the wall or partition adjacent to which they are placed, if desired, and in the usual or any preferred manner, and other changes 100 in and modifications of the construction herein described may be made, within the scope of the appended claims, without departing from the spirit of my invention or 105 sacrificing its advantages.

It will also be understood that in order to accomplish the best possible results the rods *d* must be locked in the legs *c* so that they will not rotate in said legs and so that they cannot be moved longitudinally thereof.

Having fully described my invention, what I claim as new and desire to secure by Letters Patent, is:

- 10 1. The herein described leg for tubs or like receptacles made of earthenware, said leg being also made of earthenware and being reinforced by a rod which is passed longitudinally therethrough and is provided at one end with a threaded projection and at the opposite end with an anchor device which is countersunk therein and secured to said rod.
- 15

2. The herein described leg for tubs or like receptacles made of earthenware, said leg being also made of earthenware and being reinforced by a rod which is passed longitudinally therethrough and is provided at one end with a threaded projection and at the opposite end with an anchor device which is secured to said rod and which is provided with a flange on which the leg rests when in use.

In testimony that I claim the foregoing as my invention I have signed my name in presence of the subscribing witnesses this 14th day of April, 1917.

JACOB J. BRAM.

Witnesses:

C. E. MULREANY,
H. E. THOMPSON.
